CLAIM

The ornamental design for a support post collar, as shown and described.

DESCRIPTION

FIG. 1 is a top front perspective view of a support post collar showing my new design;

FIG. 2 is a view thereof in a separated configuration;

FIG. 3 is a top view thereof;

FIG. 4 is a bottom view thereof;

FIG. 5 is a front side view thereof, the rear side view being a mirror image of the front side view; and,

FIG. 6 is a right side view thereof, the left side being a mirror image of the right side.

The broken lines illustrate portions of the support post collar which form no part of the claimed design.
